Primary Examiner — Charles Hanson(74) *Attorney, Agent, or Firm* — Norton Rose Fulbright
US LLP(57) **CLAIM**

The ornamental design for an harp wrist plate design, as shown and described.

DESCRIPTION

FIG. 1 is a perspective view of the harp wrist plate design;
FIG. 2 is a front view thereof;
FIG. 3 is a rear view thereof;
FIG. 4 is a right side view thereof;
FIG. 5 is a left side view thereof;
FIG. 6 is a top view thereof; and,
FIG. 7 is a bottom view thereof.

The broken lines showing on the harp wrist plate design are for the purpose of illustrating environmental structure and form no part of the claimed design.
